MOBILE SHELF UNIT OR THE LIKE

Kim Yamasaki, Lombard, Ill., assignor to Brunswick Corporation, Chicago, Ill., a corporation of Delaware

Filed Dec. 23, 1963, Ser. No. 77,899

Term of patent 14 years

(Cl. D33—2)

The dominant features of the design are shown in full lines on the drawing.

I claim:

The ornamental design for a mobile shelf unit or the like, as shown and described.
